(57) **CLAIM**

The ornamental design for a user interface for computer display, as shown and described.

DESCRIPTION

The file of this patent contains at least one drawing executed in color. Copies of this patent with color drawings(s) will be provided by the Patent and Trademark Office upon request and payment of the necessary fee.

FIG. 1 is a front view of a user interface for a computer display showing our new design;

FIG. 2 is a front view of a second embodiment thereof; FIG. 3 is a front view of a third embodiment thereof; and, FIG. 4 is a front view of a fourth embodiment thereof.

The broken line drawings of a computer display, windows, words, letters, numbers and other features in all views are for illustrative purposes only and form no part of the claimed design.
